United States Patent Office

JAMES COLBATH, OF WORCESTER, MASSACHUSETTS.

Letters Patent No. 69,772, dated October 15, 1867; antedated September 28, 1867.

IMPROVEMENTS IN VALVES FOR STEAM ENGINES.

The Schedule referred to in these Letters Patent and making part of the same.

Be it known that I, JAMES COLBATH, of Worcester, in the county of Worcester, and State of Massachusetts, have invented a new and useful Improvement in Automatic Steam-Valves for Steam-Pumps, of which the following is a full, clear, and exact description, reference being had to the accompanying drawings, making a part of this specification, in which—

Figure 1 is an elevation of the valve-chest.

Figure 2 is a longitudinal vertical section of the same.

Figure 3 is an elevation of the cylinder-valve.

Figure 4 is an elevation of the same.

Figure 5 is a transverse section of the cylinder-valve on the line M N of fig. 3, and

Figure 6 represents a portion of the piston or valve-rod.

Similar letters indicate like parts in the several figures.

In all cylindrical valves as heretofore used with a rapid reciprocating motion, the pressure of steam, combined with the weight of the cylinder-valve, soon causes the parts which are in contact with one another to wear off, and thus render the valve leaky and inefficient. To overcome this difficulty, to simplify the construction of the valve, and insure its perfect operation, is the object and purpose of my invention; and the invention consists in the employment of a reciprocating piston, in combination with a cylindrical piston-valve, the parts of both of which are so constructed and arranged that when the said piston is moved, by its connection with the operating parts of the engine, in one direction, steam will be admitted to the said piston-valve, and thus cause it to move in the proper direction.

The invention also consists in an enlarged recess, to extend partially around near the ends of the cylindrical piston-valve, in combination with apertures in the ends of the valve for the purpose of balancing the valve and reducing the friction on the same.

Referring to the drawings, A, figs. 1 and 2, represents the steam-chest, supposed to be attached to the top of a steam-cylinder. The piston or valve-rod B passes through the steam-chest, and is fitted in steam-tight stuffing-boxes C C'. Within the steam-chest A is fitted, so as to slide freely, a cylindrical piston-valve, D, which also slides freely on the piston B. The said piston-valve D is prevented from rotating within the steam-chest by means of a screw or pin, a, fitting within an oblong recess, b, as shown in fig. 1. The piston-valve D is provided with two annular grooves c c', connected on the upper side by a passage, d, and communicating with the inlet-ports f f', leading to the steam-passages of the steam-cylinder. A chamber, H, on the under side of the valve D, communicates with the exhaust g. The piston B is provided with steam-passages and with inlet and outlet-ports, as shown in fig. 2 at m m', l l', and n n', by means of which steam is allowed to pass from the valve D into the spaces o o' at each end of the steam-chest A. The steam from the boiler enters the steam-chest A through the pipe E, over the passage d, which latter it fills, and also the two annular grooves c c', and, as the grooves come respectively opposite their corresponding inlet-ports, the steam will pass to the steam-cylinder. This portion of the piston-valve D will thus operate similarly to an ordinary slide-valve. Steam passes through the aperture i, fig. 2, of the cylindrical valve D, and thence through the passages l l', m m', and n n', to the spaces o o', between the ends of the cylindrical valve D and the steam-chest heads, and thus a reciprocating motion is imparted to the cylindrical piston-valve D, according to the position of the piston B. The valve D is formed with a recess or groove extending around the same, near each end, as shown at p' q', fig. 3. A portion of the said recess q' on the under side of the valve is much larger or wider than the other portion p', and communicates by means of openings r r' with the spaces o o', and thus steam is admitted to the enlarged portion, and, acting upon a larger area, serves to counteract the weight of the valve D, by the excess of steam pressure upon the said valve, and thus the latter becomes a balanced valve. The apertures s s' connect the spaces o o' with the chamber h, which latter communicates with the exhaust g.

Having thus described my invention, what I claim as new, and desire to secure by Letters Patent, is—

1. The combination of the piston B, constructed as described, with the cylindrical piston-valve D, operating as and for the purpose set forth.

2. The enlarged recesses q' near the ends of the piston-valve D, in combination with the apertures r r', communicating with the spaces o o' in the steam-chest, as and for the purpose specified.

In testimony whereof I have signed my name to this specification in the presence of two subscribing witnesses.

JAMES COLBATH.
